UNITED STATES PATENT OFFICE.

LE ROY MARLAY, OF GALION, OHIO.

ADJUSTABLE WAGON-BOX.

SPECIFICATION forming part of Letters Patent No. 780,299, dated January 17, 1905.

Application filed July 20, 1903. Serial No. 166,816.

To all whom it may concern:

Be it known that I, LE ROY MARLAY, a citizen of the United States, residing at Galion, in the county of Crawford and State of Ohio, have invented certain new and useful Improvements in Adjustable Wagon-Boxes, of which the following is a specification.

This invention relates to an improvement in adjustable wagon boxes or racks, and has in view the provision of a simple and practical form of adjustable supporting-bracket arranged in connection with side rack-wings to adapt the wagon box or body for a variety of purposes—such as a straw-rack, wood-rack, fodder-rack, hay-rack, potato-box, apple-box, corn-box, or box for grain of any kind—besides for the general purposes of a wagon-box.

To this end the invention contemplates an improved type of supporting-bracket arranged in a series at each side of the wagon-box in connection with the side rack-wings and so constructed as to be easily and quickly adjusted for setting the side rack-wings at any angle from the perpendicular to the horizontal, whereby the wagon-box can be instantly changed for all kinds of loading and unloading.

A further object of the invention is to provide a form of adjustable supporting-bracket wherein the parts are protected from mud and weather conditions, besides embodying means for rigidly holding the rack-wings locked in their set positions without possibility of becoming displaced through loosening of the fastenings in passing over rough roads with the load surging back and forth within the wagon-box.

With these and many other objects in view, which will more readily appear as the nature of the invention is better understood, the same consists in the novel construction, combination, and arrangement of parts, which will be hereinafter more fully described, illustrated, and claimed.

The essential features of the invention for carrying out the objects above specified are necessarily susceptible to modification without departing from the scope of the invention; but preferred embodiments of the latter are

shown in the accompanying drawings, in which—

Figure 1 is a perspective of an adjustable wagon-box fitted with the supporting-brackets contemplated by the present invention, the view showing a preferred form of the brackets with the rack wings or boards held perpendicularly to provide a deep wagon-box for any desired purpose. Fig. 2 is a similar view showing the side wings lowered to provide a rack for hay or other material. Fig. 3 is an enlarged detail sectional view of one of the brackets shown set at an angle between the perpendicular and horizontal. Fig. 4 is a detail sectional view on the line 4-4 of Fig. 3. Fig. 5 is a similar view on the line 5-5 of Fig. 3.

Like reference-numerals designate corresponding parts throughout the several figures of the drawings.

In carrying out the invention no change is involved in the manner of mounting the wagon-box upon the running-gear, and in its general organization the wagon-box essentially consists of a body 1, comprising a bottom board or floor 2, the short upright side-boards 3, arising from the side edges of the bottom board or floor, and the end boards or gates 4 and 5, one of which (designated by the numeral 4) may have fitted thereto the usual ladder 6 and the other of which boards or gates (designated by the numeral 5) may constitute the tail-board, which is removable and replaceable, as indicated in Figs. 1 and 2 of the drawings.

The present invention involves, associating with the longitudinal side-boards 3, the folding side wings 7, designed to be moved to upright positions within the vertical plane of the side-boards 3 to form therewith a part of the wagon sides when employed as a box for general purposes and also designed to be swung out to various angular positions between the perpendicular and horizontal to convert the box into a rack for carrying hay or other materials. This adaptation of the folding side wings 7 necessitates the hinging thereof at the top edges of the side-boards 3, and this is accomplished through the medium of a series of adjustable supporting-brackets

8, arranged at the opposite sides of the wagon-box, as plainly shown in Figs. 1 and 2 of the drawings. Any number of the adjustable supporting-brackets 8 may be employed at each 5 side of the wagon-box, according to the length thereof and the reinforcement desired, and as all of the said brackets are duplicates a description of the construction of one will suffice for the others. In the use of the adjustable supporting-brackets 8 it will of course be understood that the folding side wings 7, carried thereby, may consist of an imperforate board, as suggested in Figs. 1 and 2.

Referring particularly to the construction 15 of the individual brackets 8, each of the same essentially consists of two members—namely, a base member 9 and a swinging adjustable arm member 10, to which latter is bolted or otherwise suitably secured the folding side 20 wings 7. In the preferable construction these bracket members are made of light sheet-steel bent to the required shape. In the form of bracket illustrated in Figs. 1 to 5, inclusive, of the drawings the base or stationary member 25 9 is of an approximate rectangular shape and essentially consists of a sheet-metal blank folded upon itself to provide an upright flat web portion 10^a, and at what may be properly termed its "bottom" and "rear" edges 30 the blank is flanged outward to provide the right-angularly-disposed attaching-flanges 11, which receive the bolts or other fastenings for securing the base member of the bracket in the angle between the bottom board or floor 35 2 and the projecting end of a bottom cleat 12, a series of which cleats are arranged beneath the box-body in the usual manner and whose ends project beyond the plane of the side-boards 3 thereof, as plainly shown in Figs. 1 40 and 2. The projecting ends of the bottom cleats 12 provide a rest upon which the bottom flanges of the base members 9 of the brackets are secured, while the upright rear edge flanges of said bracket members are 45 bolted to the outer sides of the side-boards 3. In the preferable construction of the base member 9 of each bracket the flanged edges thereof are reinforced by a cap plate 13, having turned edge flanges 14 seamed over the 50 edges of the bottom and rear flanges 11 of the base member 9.

At the upper rear corner the base member 9 of each bracket is provided with a pivot-ear 55 15, receiving the pivot 16 for pivotally connecting thereto one corner of the swinging adjustable arm member 10. In the preferred construction being described the swinging adjustable arm member 10 is also constructed from a sheet-metal blank bent and stamped to form 60 a doubled supporting-flange 17, projecting at

each side of the plane of the body thereof, and to which flange is secured the folding side wings 7. In addition to the doubled supporting-flange 17 the blank from which the arm member is formed is extended from one side 65 of the flange 17 to provide the parallel cheek-pieces arranged in spaced relation to form a casing or housing part 18. This casing or housing part 18 constitutes a keeper element for receiving the web 10^a of the base member 70 9 and working thereover in the adjustment of the arm 10 to different angular positions. By reason of the casing or housing 18 working over the web portion 10^a of the base member 9 it will be obvious that the entire 75 bracket is strengthened and reinforced, while at the same time the two members of the bracket are held in constant alignment at all times. Furthermore, the telescoping construction causes the upper or arm member of 80 the bracket to serve as a complete covering for the lower or base member to protect the same from mud, rain, or dust in any position.

The web portions of both members of each bracket are provided with a series of adjustment-holes 19, struck on the arc of a circle, with the pivot 16 as the center and adapted to be brought into register to receive the fastening-pin 20, preferably in the form of a bolt-nut. It is obvious that the construction 85 described permits the side wings 7 to be adjusted to any angle between the perpendicular and horizontal, according to the use of the wagon.

Having thus described the invention, what 90 is claimed, and desired to be secured by Letters Patent, is—

In an adjustable wagon-box, the combination with the side-boards and the folding side wings, of adjustable supporting-brackets each 100 comprising a stationary base member consisting of a sheet-metal web flanged at its bottom and rear edges and provided with a reinforcing-cap thereat, a swinging adjustable arm member pivoted to the rear upper corner of 105 the base member and consisting of a folded sheet-metal blank having a doubled supporting-flange and parallel cheek-pieces producing a housing part telescoping over the web of the base member, said web of the base 110 member and the housing part of the arm being provided with a series of adjustment-holes designed to register, and a fastening-pin for locking the arm in its set position.

In testimony whereof I affix my signature in 115 presence of two witnesses.

LE ROY MARLAY.
